(57) **CLAIM**

The ornamental design for a welding simulator console, as shown and described.

DESCRIPTION

FIG. 1 is a perspective view of an embodiment of a welding simulator console;

FIG. 2 is a front view of the welding simulator console of the embodiment illustrated in FIG. 1;

FIG. 3 is a left side view of the welding simulator console of the embodiment illustrated in FIG. 1;

FIG. 4 is a right side view of the welding simulator console of the embodiment illustrated in FIG. 1;

FIG. 5 is a top view of the welding simulator console of the embodiment illustrated in FIG. 1;

FIG. 6 is a rear view of the welding simulator console of the embodiment illustrated in FIG. 1, the bottom of which is unornamented;

FIG. 7 is a perspective view of a second embodiment of a welding simulator console;

FIG. 8 is a front view of the welding simulator console of the embodiment illustrated in FIG. 7;

FIG. 9 is a left side view of the welding simulator console of the embodiment illustrated in FIG. 7;

FIG. 10 is a right side view of the welding simulator console of the embodiment illustrated in FIG. 7;

FIG. 11 is a top view of the welding simulator console of the embodiment illustrated in FIG. 7; and,

FIG. 12 is a rear view of the welding simulator console of the embodiment illustrated in FIG. 7, the bottom of which is unornamented.

The broken lines shown in the Figures are for illustrative purposes only and form no part of the claimed invention.
